UNITED STATES PATENT OFFICE.

SYLVANUS ALBERT REED, OF NEW YORK, N. Y., ASSIGNOR TO THE REED PROPELLER CO., INC., OF NEW YORK, N. Y., A CORPORATION OF NEW YORK.

TWISTING MACHINE.

Application filed June 9, 1925, Serial No. 35,947, and in France October 15, 1924.

My invention relates to machines for twisting a metal object, and more particularly a plate of annealed metal, such as aluminum base alloys, for example duralumin, and is especially applicable in the manufacture of aeronautical propellers made from an elongated plate of metal.

In the operation of twisting machines, there is a reactive stress against the machine, which is usually taken up by a massive base or by attachment to the building or to foundations or to the ground, each involving a considerable amount of bulk, weight and expense. I have discovered that by transmitting the torque of one point of attachment of the object being twisted to the other point of its attachment, as by means of a tube, such bulk, weight, and expense may be substantially reduced, and I have invented a machine embodying this principle which is an improvement on previous machines designed for this purpose.

I have illustrated a type of my invention in the accompanying drawings, wherefore in;

Fig. 1 is a diagrammatic representation, in perspective, of the machine and the plate or object being twisted;

Fig. 2 is a plan view, Fig. 3 an end view, and Fig. 4 a cross-sectional view of a machine made in accordance with my invention;

Fig. 5 is a side elevation, and Fig. 6 a longitudinal section of the said machine.

Referring to the drawings, 1 is a metal torque-transmitting tube, 14 is a shorter tube telescoped into one end of the tube 1. 3 indicates a pair of clamps diametrically attached to the tube 14, while 4 is a pair of clamps diametrically attached to the tube 1, which is open at both ends and is secured in horizontal position to a bench 15. The telescoping tube section 14, is also open at both ends and its outer end is provided with a fixed annular bearing 30.

2 is an elongated metal plate undergoing twisting and passes through tube 1 and the tube section 14 and is firmly embraced by the clamps 3 and 4. If the tube 14, is rotated by mechanical means reacting against the tube 1, the plate 2 will be twisted and no massive or bulky part will be required in the machine. The pair of clamps 3 grip one part of the plate to be twisted and the pair of clamps 4 grip another part of said

plate a suitable distance from said clamps 3. The tube 14, has attached to its outer end a large disc wheel 16, with a geared rim, which disc when rotated rotates the tube 14. 17 and 18 are yokes firmly attached to the tube 1, and carrying between them shafts 19, to which are attached pinions 20, which engage the geared rim of the disc wheel 16. Each shaft 19, has a large gear-wheel 21, fixed thereto and a pinion 21' which meshes therewith is secured on the shaft 22', of the worm-wheel 22, which is driven by a worm 23, actuated by shaft 24, to which the worm is fixed. The worm-shaft 24, which carries a worm 22 at each end, is operated by the gear wheel 25, driven through a train of gears 25' and 25'', by an electric-motor 26, which is mounted on the shelf 26' attached to the tube 1.

All bearings of all shafts and gears, except the disc-wheel 16, are attached to the tube 1. Therefore, the reactive stresses of all of the mechanism transmitting the motive power of the disk-wheel 16, to the tube 14, reacts against the tube 1. A single worm-shaft 24, drives the duplicate sets of gears 21 and therefore pinions 20, which pinions exercise always a balanced rotative effort on the disk-wheel 16 and the tube 1.

The relation of the elements in the gear trains may be so adjusted as to produce a very slow twist against a very great rigidity resistance by a high speed low power motor.

27 indicates guide-bars diametrically fixed to the inner walls of the tube 1, and parallel with its axis, and the clamps 4, are movable longitudinally to different places in the tube 1. In this manner a plate may be firmly held by one pair of clamps 3, and a progressive twist of varying ratio be given by successively advancing the pair of clamps 4, to grip the plate at successive points.

I wish to be understood as not limiting my invention to the particular constructions of the various different parts thereof as herein shown, as it is manifest that various modifications may be made in the same without however departing from the spirit of the invention.

Having thus described my invention, what I claim and desire to secure by Letters Patent, is:

1. In a machine for twisting metal plates and other objects, holding means for engaging the work at spaced points, and tubular

connections between said holding means constructed and arranged so that torque stress is transmitted from one to the other of said holding means and thence to the work.

2. In a machine for twisting metal plates and other objects, two clamps adapted to engage the object to be twisted, a torque-transmitting tube surrounding the object and one of said clamps being secured to said tube, the other clamp being adapted for rotary displacement around the axis of said tube.

3. In a machine for twisting metal plates and other objects, a torque-transmitting tube and transverse object-engaging members, one secured to one region of the tube and the other rotatable about an axis coincident with that of the tube and a pair of rotating means having their reaction fulcrums attached to another region of the tube, a balanced mechanical coupling relation between the rotatable and the fixed members, and balanced means for rotating the rotatable members.

25 4. A twisting machine for twisting metal plates and other objects constructed in accordance with claim 3, wherein one of the transverse object-engaging members is fixed to one region of the tube and the other is displaceable in relation thereto.

5. A twisting machine for twisting metal plates and other objects, including a tube carrying interior sets of clamps longitudinally separated, part of the set of clamps being fixed and part of the set rotatable about the tube axis by means secured to the tube walls and operating by rotation to twist an object clamped by the said sets of clamps, and means for effecting said rotation.

40 6. A twisting machine for twisting metal plates and other objects, comprising holding means for engaging the work at spaced points, tubular connections between said

holding means constructed and arranged so that the torque stress is transmitted from one to the other of said holding means and thence to the work, said holding means being capable, after partial twisting, of re-engaging the work at different successive points to produce a progressive twist of varying ratio by successive advancement of the holding means.

7. In a machine for twisting metal plates and other objects, holding means for engaging the work at spaced apart points, tubular connections between said holding means constructed and arranged so that torque stress is transmitted from one to the other of said holding means and thence to the work, said holding means being relatively adjustable toward and away from each other to engage the work at successive points.

8. In a machine for twisting metal plates and other objects, two clamps adapted to engage the object to be twisted at spaced apart points, a torque transmitting tube surrounding the object, and one of said clamps being mounted therein and adjustable longitudinally thereof, the other clamp being adapted for rotary displacement around the axis of said tube.

9. In a machine for twisting metal objects, a torque-transmitting tube having an interior longitudinally adjustable clamping means for holding the work, a floating annular disk gear wheel concentric with said tube and provided with clamping means spanning the opening therein for engaging another part of the work positioned in the axis of said tube, and balanced inter-reactive power means between said disk and tube.

In testimony whereof, I have hereunto set my hand.

SYLVANUS ALBERT REED.
